UNITED STATES PATENT OFFICE.

SALO WOHL, OF LONDON, ENGLAND, ASSIGNOR TO THE WOHL MINERAL OIL PRODUCTS (1910) LIMITED, OF LONDON, ENGLAND.

PROCESS OF TREATING PETROLEUM OR OTHER HYDROCARBON OILS.

1,081,801.

Specification of Letters Patent. Patented Dec. 16, 1913.

No Drawing.

Application filed April 26, 1910. Serial No. 557,716.

To all whom it may concern:

Be it known that I, SALO WOHL, a subject of the Emperor of Germany, residing at London, England, have invented certain new and useful Improvements in Processes of Treating Petroleum or other Hydrocarbon Oils, of which the following is a specification.

This invention relates to improvements in process of treating petroleum or other hydrocarbon oils such as kerosene, petroleum distillates, especially light hydrocarbon oils of a specific gravity approximating from 0.680 to 0.860 and lighting oils, benzin, shale oils and pitch oils.

The object of the invention is to produce a highly rectified or refined and substantially odorless oil together with a valuable residue.

20 The process according to this invention for treating oils of the kinds described consists in adding to the oil an alkaline extract of seaweed and also a saponaceous substance with or without sulfuric acid.

25 According to one modification of the process the seaweed is added to an alkaline lye and the saponaceous substance is afterward incorporated with the solution thus formed.

According to a further modification the 30 saponaceous substance may be prepared by treating a saponaceous plant with a solution of alkaline lye.

In a preferred process the alkaline solution containing the seaweed extract is mixed 35 with a saponaceous substance and the mixture is added to the oil to be treated. Sulfuric acid is then added causing a brisk effervescence. The oil can then be separated by decantation or by any other convenient 40 method. The residue remaining after the removal of the oil is of value for both commercial and scientific purposes.

One method of carrying this invention into effect is as follows:—A mucilage is prepared from seaweed in the following manner. A solution of carbonate of soda in water at 90–100° F. is made in the proportion of 1 lb. of carbonate of soda to 1 gallon 50 of water. Quicklime is then added in the proportion of about $\frac{1}{2}$ lb. to the gallon and the mixture is stirred and allowed to settle. The supernatant liquid will be a solution of caustic soda, enough lime having been added to carry down all the carbonic

acid. The proportions given above are 55 those preferred in practice and will give a concentrated solution, although no limitation is to be imposed upon the invention by the proportions given. Seaweed, preferably in a powdered condition, is then added in 60 the proportion of about $\frac{1}{2}$ –1 lb. of seaweed to each gallon of water employed, and the whole is boiled until a thick mucilaginous fluid is obtained. To this fluid various chemical reagents may be added (for the 65 purpose of precipitating certain impurities from the mineral oil), for example common salt in the proportion of $\frac{1}{2}$ lb. per gallon or iron oxid in the proportion of $\frac{1}{2}$ –1 lb. per gallon may be added or both these ingredients may be added together. A detergent is then prepared by forming a similar alkaline lye to that just described and treating with it a saponaceous plant, nut, bark or the like, referred to specifically hereinafter, 70 the weight of saponaceous material being 30–50% of the weight of the alkaline lye employed. To the detergent may be added sulfate of iron in the proportion of 5–10% of the dry weight of the saponaceous material.

The method of applying the invention is as follows:—A mixture is made by adding 1 part of the detergent to 3 parts of the mucilage and of this mixture 5–10% is added 75 to the oil to be treated. As an example mineral oil of the nature of kerosene is diluted with water in the proportions of 5 gallons of oil to $2\frac{1}{2}$ gallons of water. 10% ($\frac{1}{2}$ gallon) of detergent is then added and also $\frac{1}{2}$ lb. of sulfuric acid (1%–2%) either in the refined or commercial form. The whole is then stirred, when a brisk effervescence will take place followed by a separation of purified oil from the remainder of the liquid. 80 This separation takes place after about 10–20 minutes and the purified oil may then be decanted from the remainder of the liquid.

Benzin, petrol or similar spirit or illuminating oil treated as described will have a higher flash point, will be practically odorless and will not readily give off smoky fumes when consumed for either heating or for motive power purposes. An illuminating oil distillate treated by this process will in addition allow of a larger fraction being taken from crude oil. A crude

petroleum or crude distillate may be treated in the manner described and afterward be separated by fractional distillation.

It is a feature of the resulting oil that it is freed from sulfur and does not generate carbon monoxide gas when burned or when used in an internal combustion engine.

It is possible to employ almost any class of seaweed but it is preferred to use that known as *Algae*, which has a form resembling maidenhair fern. It is not essential that the seaweed should be broken up and ground although it is advantageous to the process to do so.

15 The saponaceous plants employed may be selected from any of the following:—quillai bark, *Acacia concinna* bean, *Entada scandens* bean, a big nut called by the natives of India and Mexico the "ritta" nut.

20 It is within this invention to add the saponaceous plant directly to the seaweed extract instead of extracting it in the manner described.

Although one particular method has been 25 described as an example it is obviously possible to modify the process and proportions of the ingredients provided that the spirit of the invention is not departed from.

What I claim as my invention and desire 30 to secure by Letters Patent is:—

1. A process for the treatment of oils of the kinds described which consists in adding to the oil an alkaline mucilage prepared

from seaweed and a vegetable saponaceous alkaline detergent. 35

2. A process for the treatment of oils of the kinds described which consists in adding to the oil an alkaline solution prepared from seaweed and a vegetable saponaceous alkaline detergent and sulfuric acid. 40

3. A process for the treatment of oils of the kinds described which consists in adding seaweed to an alkaline lye and thereafter adding a saponaceous substance, the mixture thus formed being added to the oil. 45

4. A process for the treatment of oils of the kinds described which consists in adding to the oil a saponaceous substance prepared by treating a saponaceous plant, nut or bark with a solution of alkaline lye. 50

5. A process for the treatment of oils of the kinds described which consists in adding to the oil a solution comprising in admixture (a) a mucilage prepared by treating dried and powdered seaweed with a solution of soda-lye; (b) a solution prepared by treating a saponaceous plant, with a solution of soda-lye. 55

In testimony whereof I have signed my name to this specification in the presence of 60 two subscribing witnesses.

SALO WOHLÉ.
